W. E. GREENAWALT

ELECTROLYTIC APPARATUS

Filed April 7, 1923

FIG 1

FIG 3

FIG 5

INVENTOR
William E. Greenawalt

UNITED STATES PATENT OFFICE.

WILLIAM E. GREENAWALT, OF DENVER, COLORADO.

ELECTROLYTIC APPARATUS.

Application filed April 7, 1923. Serial No. 630,634.

To all whom it may concern:

Be it known that I, WILLIAM E. GREENAWALT, a citizen of the United States, residing in the city and county of Denver and State of Colorado, have invented certain new and useful Improvements in Electrolytic Apparatus, of which the following is a specification.

The apparatus is designed more particularly for the precipitation of copper, and the regeneration of ferric salts, in leach solutions, in processes set forth in my pending applications, Serial No. 450,460, filed April 16, 1918; Serial No. 380,361, filed May 10, 1920; and Serial No. 520,241, filed December 6, 1921, although it is not intended to limit the apparatus to any particular use.

It has long been known that in the electrolysis of copper leach solutions containing salts of iron, effective depolarization prolongs the life of the anodes in the deposition of copper and in the regeneration of ferric salts, and this is the case whether metal or carbon anodes are used.

It is possible, under effective depolarization, to use carbon anodes in the deposition of copper from sulphate solutions.

It has been observed, in precipitating copper from chloride solutions, that under the action of a fairly high current density and in the presence of a depolarizing agent, such as ferrous sulphate or sulphur dioxide or both, that the copper can be deposited in loose granular form and of high purity, and that this loose granular copper drops from the cathode from time to time, and that the process may be carried on indefinitely, or at least for a considerable time, without removing the cathodes from the cells to strip them of remaining adhering copper. With a chloride solution, carbon anodes are a practical necessity, because metal anodes are very rapidly disintegrated, while carbon anodes last indefinitely.

Whether chloride or sulphate solutions are used, it is necessary to flow the solution through the cells quite rapidly and evenly so as to avoid the undue accumulation of ferric salts, which would not only have an injurious effect on the anodes, but would also tend to re-dissolve the deposited copper, and thus greatly reduce the efficiency of the deposition.

The use of carbon anodes in copper deposition has always presented a difficult construction problem, because the individual

pieces of carbon, from which a complete anode is made, are not very large, and the manufacturing limit of individual pieces is about 2 x 8 x 48 inches. In assembling these pieces to make a complete anode with proper electrical connections, it has been customary to cast the ends of the pieces in lead. This served to hold the pieces together and to make electrical connection. These anodes are then suspended in the tank, or cell, in the ordinary way, by means of copper rods contacting with the busbars of the cells.

To meet the conditions specified and to simplify the use of carbon anodes in the deposition of the copper, I have invented the apparatus which may best be described by reference to the accompanying drawings, in which Fig. 1 represents a longitudinal section: Fig. 2 the corresponding transverse section: Fig. 3 and Fig. 4 details of the electrodes and conductors, in transverse and longitudinal sections, respectively; and Fig. 5 a transverse section of a modification of the apparatus, showing an enclosed cell.

Referring to the figures, 1 represents a tank adapted to contain the electrolyte; 2 shows the liquid inlet and 23 the liquid outlet. Both the inlet and the outlet are arranged to distribute the liquid uniformly across the tank or cell. 4 are the carbon anodes, which are supported on longitudinal strips 5, and these strips are supported in turn by cross pieces 6 in the lower portion of the tank. The bottom of the tank slopes toward a central outlet 3, through which the precipitate, or insoluble material, may be washed from the cell. The cross pieces 6 are preferably kept a little above the bottom of the tank to facilitate washing. The longitudinal strips 5 are grooved to maintain the bottom of the anodes in alignment, while at the same time offering a way to support the individual anode pieces without casting or joining them together at the top.

To make electrical connection with the anodes, it is preferred to drill a hole in the top of each carbon and insert one end of the conductor rod 8 into the hole and then pour in moulten lead to secure the rod to the carbon and to make good electrical connection between the rod and the carbon. The cast lead is shown by 10. The rod 8 may be made of lead or copper. To protect the rod from attack of the electrolyte at or near the surface, it is surrounded by an insulator 12, which is slipped over the rod, and which

may be permanently fixed to the rod or made removable. The insulator 12 may be made of glass, stoneware, rubber, or the like.

The positive conductors are shown by 7 arranged longitudinally with the cell. The conductor rods 8 of the individual anode pieces are secured to the conductors by bolts 9, which may be made as tight as desired to give good electrical connection. The conductor rod 8 may also be soldered to the conductor 7 if desired: this would give practically a perfect electrical connection, and it would not have to be disturbed until the anodes are worn out. The positive conductor 7 rests on cross bars 13, placed at regular intervals, and is insulated therefrom by the insulator 20.

The cathodes 18, which may be lead or copper sheets, are suspended in the tank from the rods 17, and these rods are supported on, and make electrical connection with copper cross bars 16, and the cross bars 16 make electrical connection with the main negative conductor 21 at the side of the tank. In order to save copper, the cross bars 16 are supported by the cross bars 13. The bars 13 are preferably made of an iron bar 14 enclosed or coated with lead 15. Such a bar gives the desired strength and resists attack from acid fumes or spilled electrolyte. The connection between the copper bars 16 and the negative conductor 21 may be made tight with a screw or solder, or both, as desired, since the copper bars 16 are more or less permanently positioned until worn out. The removable connection is between the rods 17 and the copper bars 16, so that the cathodes 18 may be removed and replaced as desired, with a minimum number of loose connections. This is of some importance, since much of the energy in copper deposition with the electric current is consumed by the poor electrical contact with removable connections. Where the cathodes are more or less permanent, as in the present arrangement, even the cathodes 18 may be soldered to the cross bars 17, to reduce electrical resistance which is due frequently to poor electrical contact between the cathode and the suspension bar 16.

When gases, such as sulphur dioxide, are applied to the electrolyte, or if there is a corrosive gas liberated as the result of electrolysis, it is preferred to work with a closed cell, as shown in diagrammatic section in Fig. 5. In such cases the electrical contact between the suspension rod 17 and the cross bar 16 may be made with a burned or soldered joint. This would always insure good electrical contact, since the contact would not be effected by corrosive gases. An exhauster, 24, working under a slight suction, prevents any gas from escaping into the cell room and contaminating the atmosphere in the vicinity of the cell.

A brief description of one way of operating the apparatus may be given. If a copper chloride solution is used as the electrolyte, or say, a copper chloride solution as obtained from leaching ores; it is first treated with sulphur dioxide to reduce the cupric chloride to the cuprous condition and the ferric chloride to the ferrous condition. This reduced solution is then flowed into the apparatus as described, and electrolyzed. With a fairly high current density, say, from 20 to 50 amperes per square foot, copper is deposited in a somewhat granular form on the cathode, and this deposit accumulates until it becomes too thick to support itself; it then drops to the bottom of the tank, where it accumulates in a granular form until it is desired to remove it. The chlorine liberated at the anode combines, first with any excess sulphur dioxide and is thus rendered harmless to re-dissolve deposited copper. Similarly, it reacts with the ferrous and cuprous salts before it appreciably attacks the deposited copper at the cathode, so that practically a theoretical efficiency is possible in the deposition of the copper, provided the ferric and cupric salts are not allowed to accumulate above a certain economic limit, say 0.25% for both combined.

This may be controlled by the rate of flow through the tank or cell. The issuing electrolyte is then again treated with the gas and returned to the cell, and this cycle is continued until the copper is sufficiently removed from the solution, and then the solution is returned to the ore.

To facilitate the flow through the cell, the electrodes are placed longitudinally with the cell, so that the electrolyte in flowing through it, contacts all the electrodes and stagnant eddys or pools are avoided. The rate of flow through the cell should be quite rapid, and the amount of ferric and cupric salts in the outflowing solution will determine the minimum flow.

When the copper has accumulated sufficiently in the bottom of the cell, the cell is drained and the copper washed out through the outlet 3 into a launder which leads to a proper apparatus or receptacle, to separate the copper from the solution. A portion of the copper solution will ordinarily be used to wash the copper from the cell to avoid unnecessary dilution of the solution, although water may be used if desired. It will not ordinarily be necessary to remove any of the electrodes, under the assumed conditions.

If, however, a low current density is used, or if a sulphate solution is used, the copper will accumulate on the cathodes, and then the cathodes have to be removed and stripped, or replaced, in the usual way; but even in that case the anodes need not in any way be molested.

The apparatus is eminently adapted to large electrolytic units. If, for example, it is desired to use a current of 15,000 amperes, with six rows of anodes, a cell about 60 feet long would be required. With carbons 4 feet long, one complete anode row would be about 50×4 feet in area, and have 400 square feet for both sides, or 2000 square feet in all. This would indicate an anode current density of $7\frac{1}{2}$ amperes per square foot, and a current 1500 amperes flowing through the two outside conductors and of 3000 amperes flowing through each of the four intermediate conductors, 7. This current would be delivered to the cell and electrolyte, without any break or removable joint in the circuit. If at any time any of the anodes should give trouble on account of corrosion or regular wear, any individual anode piece may be removed and replaced by a new one without interfering with the others or with the operation of the cell. Any of the cathodes may be removed at any time without interfering with the operation of the cell.

The more or less permanent contact between the leading in metal rods 8 and the electric conductors 7, made possible by bolting or soldering, facilitates the transmission of large currents without any undue increase of resistance at the points of contact.

In the electrolysis of leach copper solutions, and in the oxidation of ferrous iron, for example, it may be advisable to agitate the electrolyte. This agitation should be mild and should be free from any unusual mechanical difficulty. In the past, effective agitation of the electrolyte presented great difficulties. Purely mechanical agitation is too complicated. Air agitation has been usually adopted, but it has been found exceedingly difficult to apply the air satisfactorily, especially for mild agitation. If air is introduced in very small jets in the usual way, there is danger of the injector becoming clogged, and if introduced in large jets, much air is wasted, the agitation is too violent, and the air is not effectively atomized and distributed.

I have found that an excellent way of agitation, as also aeration, is to introduce the air in moderate size jets or streams, through an injector so arranged that liquid from the tank flows into the injector by the suction induced by the air, and a mixture of air and liquid is ejected from the injector into the surrounding liquid in the tank. This method of injecting the air, breaks the air up into fine bubbles, or atomizes it, so that it ascends through the electrolyte in finely divided and well distributed bubbles. The injectors are preferably arranged opposite one another, so that streams of gas and liquid issuing from the various injectors

will penetrate one another and give a fairly uniform distribution of the gase and a uniform agitation.

In the arrangement shown in the drawings, 26 represents the injectors, taken as a whole. The air or gas pipe in the interior of the injector is shown by 27, the liquid inlet duct by 28, and the injector outlet, through which the gas and liquid are ejected, by 29. The compressed air, or gas, supply main is shown by 25.

The compressed gas, forced from the main 25, through the pipe 27, sucks a portion of the liquid from the tank into the interior of the injector through the ducts 28, and the mixture of gas and liquid is then ejected into the surrounding liquid in the tank through the outlet 29. The mixture of gas and liquid will be distributed within a range determined mostly by the pressure of the gas. The gas so ejected will be in a fine state of subdivision. The streams of gas and liquid, from opposite sides of the tank, impinge, or penetrate one another, so that the finely atomized gas will be evenly distributed over a large area, and ascends through the liquid between the electrodes. The efficiency of the gas is greatly increased by this method of applying it.

If the gas is air, it simply escapes at the top. If it is some other gas, such as sulphur dioxide, it may be caught in the hood 22, and again passed through the electrolyte until the gas is consumed. Any suitable form of exhauster-compressor 24 may be used. The injectors, when used in connection with corrosive liquid or corrosive gases, should be made of acid resisting material.

I claim:

1. In electrolytic apparatus, a tank adapted to contain the electrolyte, carbon anodes supported from below arranged longitudinally with the tank and making electric contact with longitudinally arranged conductors, and metal cathodes arranged parallel with the anodes suspended from longitudinally arranged bars, said bars making electric contact with conductors arranged transversely of the tank.

2. In electrolytic apparatus, a tank adapted to contain the electrolyte, electrodes of one polarity supported from below and arranged longitudinally with the tank and making electric contact with longitudinally arranged conductors, and electrodes of the opposite polarity suspended from above and making electric contact with conductors arranged transversely of the tank intermediate the ends of the tank.

3. In electrolytic apparatus, a tank adapted to contain the electrolyte, electrodes of one polarity arranged longitudinally with the tank and making electric contact with longitudinal conductors, electrodes of the opposite polarity arranged longitudinally

- with the tank and making electric contact with conductors arranged transversely of the tank intermediate the ends of the tank.
4. In electrolytic apparatus, a tank adapted to contain the electrolyte, a series of individual carbon anode pieces or sections arranged longitudinally with the tank to form a composite whole anode, an electric conductor arranged longitudinally with the tank over the anode, leading in rods connecting the individual anode pieces with the conductor, said rods being arranged so that any anode piece may be removed and replaced without disturbing the others.
5. In electrolytic apparatus, a tank adapted to contain the electrolyte, anodes arranged longitudinally with the tank and supported from below, electric conductors arranged longitudinally with the tank intermediate its ends over the anodes and supported on negative cross bar conductors arranged transversely of the tank, and insulators interposed between the positive and negative conductors at the area of support.
6. In electrolytic apparatus, a tank adapted to contain the electrolyte, positive electrical conductors arranged longitudinally with the tank and making electric contact with a continuous row of anodes within the tank, and negative electric conductors arranged transversely of the tank intermediate its ends and making electric contact with cathodes arranged longitudinally with the tank.
7. In electrolytic apparatus, a tank adapted to contain the electrolyte, negative electric conductors arranged transversely of the tank intermediate its ends, positive electric conductors arranged longitudinally with the tank and supported by the negative electric conductors, and means for insulating the positive conductors from the negative conductors at the points of intersection.
8. In electrolytic apparatus anodes secured in permanent relation to the positive electric conductor arranged longitudinally with the tank and cathodes arranged in removable relation to the negative electric conductor arranged transversely of the tank.
9. In electrolytic apparatus, a tank adapted to contain the electrolyte, anodes secured in permanent relation to the positive electric conductor arranged longitudinally with the tank, and cathodes arranged in removable relation with the negative electric conductor disposed transversely of the tank intermediate its end.
10. In electrolytic apparatus, a tank adapted to contain the electrolyte, electrodes of one polarity supported from below and making electric contact with an electric conductor arranged longitudinally with the tank, and electrodes of the opposite polarity suspended from above and making electric contact with an electric conductor arranged transversely of the tank.
11. In electrolytic apparatus, a tank adapted to contain the electrolyte, electrodes arranged in parallel rows longitudinally with the tank and making electric contact with conductors arranged longitudinally with the tank, said electrodes being supported from below, and means in connection with said electrode supports for maintaining the electrodes in alignment.
12. In electrolytic apparatus, a tank adapted to contain the electrolyte, electrodes arranged in parallel rows longitudinally with the tank and making electric contact with conductors arranged longitudinally with the tank, said conductors being supported at intervals by supports arranged transversely of the tank below the electrodes.
13. In electrolytic apparatus, a lower section adapted to contain the electrolyte, an upper section engaging the lower section to confine gas above the electrolyte, electrodes in the lower section arranged in parallel rows longitudinally with the lower section said electrodes being supported from below, and means for exhausting gas from the upper section.
14. In electrolytic apparatus, gas injectors in the lower portion of the tank adapted to eject a mixture of gas and liquid in substantially horizontal streams into the surrounding liquid in the tank, said injectors being arranged so that issuing streams of gas and liquid from different injectors will penetrate one another, and means for supplying gas under pressure to said injectors.
15. In electrolytic apparatus, a tank adapted to contain liquid, hollow stationary members in the lower portion of the tank having discharge passages communicating with a gas supply and with the liquid in the tank, means adapted for combining a stream of gas with a stream of liquid in said injectors and ejecting the mixture of gas and liquid into the surrounding liquid in the tank below the electrodes, and means for supplying gas under pressure to said hollow stationary members.
16. In electrolytic apparatus, a tank adapted to contain liquid, hollow stationary members in the lower portion of the tank having discharge passages communicating with a gas supply and with the liquid in the tank, means for supplying gas under pressure to the interior of said hollow stationary members and ejecting the gas with liquid into the surrounding liquid in the tank below the electrodes, said hollow stationary members being arranged so that issuing streams of gas and liquid from different hollow members will penetrate one another.

WILLIAM E. GREENAWALT.
